Primary Examiner — Mitchell I. Siegel(74) Attorney, Agent, or Firm — Birch, Stewart, Kolasch & Birch LLP(57) CLAIM

The ornamental design for a head for golf club, as shown and described.

DESCRIPTION

FIG. 1 is a first perspective view of a head for golf club;
FIG. 2 is a second perspective view thereof;
FIG. 3 is a front view thereof;
FIG. 4 is a left side view thereof;
FIG. 5 is a top view thereof; and,
FIG. 6 is a bottom view thereof.

The broken lines depict portions of the head for golf club in which the design is embodied that are not considered part of the claimed design.

The dashed lines show a boundary between the claimed design and unclaimed portions.
